LAPPING MACHINE

Herbert S. Indge, Westboro, Mass., assignor to
 Norton Company, Worcester, Mass., a corpora-
 tion of Massachusetts

Application January 24, 1941, Serial No. 375,828

4 Claims. (Cl. 51—67)

The invention relates to lapping machines, and more particularly to a machine for lapping the lapped side faces of piston rings and the like.

One object of the invention is to provide a simple and thoroughly practical lapping machine. Another object of the invention is to provide a lapping machine in which a ring-shaped object is rotatably supported while it is lapped by a rapidly reciprocating abrasive lapping element. A further object of the invention is to provide a hydraulically operated reciprocable lapping element which is adjustably supported so that it may lap either a plane side face of a work piece normal to its axis of rotation or an angular or tapered face thereon such as, for example, a piston ring tapered cross section.

Another object of the invention is to provide a piston ring lapping machine in which a pair of independent hydraulic motors are arranged to reciprocate lapping sticks in engagement with a side face of a work piece, such as a tapered piston ring, in diametrically opposed positions. A further object of the invention is to provide such a lapping machine in which the hydraulic motors and lapping sticks supported thereby are independently and angularly adjustable.

Another object of the invention is to provide a lapping machine having a motor driven rotatable work support and a hydraulically operable slide for supporting a plurality of hydraulically reciprocated lapping elements, in which a manually operable main control valve serves to control the positioning of the lapping sticks and automatically to control the stopping and starting of the work driving motor. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of the improved lapping machine, having parts broken away and shown in section, combined with a diagrammatic illustration of the hydraulic and electrical control systems;

Fig. 2 is a fragmentary vertical sectional view through the lapping machine, taken approximately on the line 2—2 of Fig. 1;

Fig. 3 is a fragmentary plan view of one of

the lapping heads, taken approximately on the line 3—3 of Fig. 1;

Fig. 4 is a fragmentary sectional view through one of the lapping heads, taken approximately on the line 4—4 of Figs. 1 and 3;

Fig. 5 is a fragmentary cross-sectional view through the lapping head of the machine, taken approximately on the line 5—5 of Figs. 1 and 2;

Fig. 6 is a fragmentary cross-sectional view, on an enlarged scale, taken approximately on the line 6—6 of Fig. 1;

Fig. 7 is a cross-sectional view, taken approximately on the line 7—7 of Figs. 3 and 4;

Fig. 8 is a fragmentary cross-sectional view, taken approximately on the line 8—8 of Fig. 7;

Fig. 9 is a fragmentary cross sectional view of a modified construction, in which the fluid pressure is used to move the lapping element to and from an operative position; and

Fig. 10 is a fragmentary diagrammatic view showing the lapping elements arranged simultaneously to lap adjacent angularly disposed faces on a work piece.

A lapping machine has been shown in the drawings, comprising a base 10 which supports a rotatable work support, such as a work head 11. The work head 11 is mounted on the upper surface of the base 10 and is provided with a rotatable spindle 12 which is supported in anti-friction bearings 13 and 14. The spindle 12 supports a chuck, such as a face plate 15, which is recessed so as to support a work piece, such as a piston ring 16.

The spindle 12 is preferably rotated by a motor driven mechanism, comprising a variable speed electric motor 17 mounted within the work head 11. The motor 17 is provided with an armature shaft 18 which supports a V-groove pulley 19. The pulley 19 is connected by means of a V-belt 20 with a V-groove pulley 21 mounted on the end of the spindle 12.

Power is supplied for the motor 17 by a suitable outside source, as represented by the power lines 22 (Fig. 1). A snap switch 23 is provided to open and close the circuit controlling the motor 17. A variable speed rheostat 24 is provided for manually controlling the speed of the motor 17 so as to thereby regulate and control the speed of rotation of the work piece 16. A normally closed limit switch 25 is connected in series with the snap switch 23 and the rheostat 24 by means of which the electric circuit controlling the motor 17 may be opened automatically to stop the rotation of the work piece 16.

after a lapping operation has been completed in a manner to be hereinafter described.

A transversely moveable lap supporting slide 30 is provided for supporting the lapping element to be hereinafter described. The slide 30 is provided with a dovetailed slideway 31 which mates with a correspondingly shaped way 32 which is fixedly mounted on the upper face of the base 10. The slide 30 is arranged so that it may be moved to and from an operative position to facilitate loading of work pieces and removing them from the machine before and after a lapping operation.

In the preferred construction, a hydraulically operated mechanism is provided for moving the slide 30 transversely in either direction, which may comprise a cylinder 33 which is fixedly mounted within the base 10 of the machine. The cylinder 33 contains a slidable piston 34 which is connected to one end of a piston rod 35. The other end of the piston rod 35 is connected to a bracket 36 which projects downwardly from the under side of the slide 30. It will be readily apparent from the foregoing disclosure that when fluid under pressure is admitted to a cylinder chamber 37 at the left-hand end of the cylinder 33 (Fig. 1), the piston 34 together with the piston rod 35 and the bracket 36 will move the slide 30 toward the right. Similarly, when fluid under pressure is admitted to a cylinder chamber 38 at the right-hand end of the cylinder 33 (Fig. 1), the piston 34 together with the piston rod 35 and the bracket 36 will move the slide 30 toward the left (Fig. 1).

A fluid pressure system is provided for conveying fluid under pressure to the cylinder 33 and also to other fluid pressure actuating mechanisms to be hereinafter described. A box-like reservoir 40 is provided within the base 10 of the machine. Fluid is pumped from the reservoir 40 by means of a motor driven fluid pump 41. Fluid is drawn by the pump 41 through a pipe 42 and conveyed through a pipe 43 to a manually operable control valve 44. An adjustable pressure relief valve 45 is connected by a pipe 46 with the pipe 43. The pressure relief valve 45 is adjusted to maintain the desired operating pressure within the fluid pressure system but is so arranged as to allow excess fluid under pressure to exhaust through a pipe 47 into the reservoir 40.

The control valve 44 is a piston type control valve comprising a valve stem 50 having formed integrally therewith valve pistons 51, 52, 53, 54, 55 and 56. The valve 44 is arranged so that it may be actuated manually by means of a manually operable control lever 57 which is pivotally supported on a stud 58 which is in turn fixedly supported on the machine base 10. The lower end of the lever 57 is yoke-shaped and is provided with diametrically opposed studs or pins 59 which engage a groove 60 formed in the valve stem 50. The valve stem 50 is shown in its extreme right-hand end position (Fig. 1), in which position the slide 30 is moved toward the left into an operative position. In this position of the parts, fluid under pressure passing through the pipe 43 passes through a pipe 61 into a cylinder chamber located between the valve pistons 54 and 55 and passes out through a pipe 62 into the cylinder chamber 38 to move the piston 34, the piston rod 35, the bracket 36, and the slide 30 toward the left to position the lapping elements to be hereinafter described in an operative position for a lapping operation. During

the movement of the slide 30 toward the left, fluid within the cylinder chamber 37 exhausts through a pipe 63, through a valve chamber formed between the valve pistons 53 and 54, and exhausts through a pipe 64 into the reservoir 40. A throttle valve 65 is provided in the pipe line 64 to facilitate control of the exhausting fluid from the cylinder 33 so as to control the speed or rate of movement of the slide 30 in either direction. An adjustably positioned stop block 66 is provided to limit the forward movement or movement of the slide 30 toward the left (Fig. 1).

After a lapping operation has been completed and it is desired to move the slide 30 to a rearward or inoperative position, the control lever 57 is moved in a clockwise direction (Fig. 1) into the broken line position 57a, which movement is transmitted to shift the control valve 44 toward the left (Fig. 1). In the left-hand end position of the valve 44, fluid under pressure from the pipe 43 passes through the pipe 61 into the valve chamber formed between the valve pistons 54 and 55 and passes outwardly through the pipe 63 into the cylinder chamber 37 to move the piston 34, the piston rod 35, the bracket 36 and the slide 30 toward the right (Fig. 1) to an inoperative position.

In the production of work pieces, such as relatively large diameter piston rings for the automotive and aeroplane engines, it is desirable to provide a highly finished surface on the flat side faces of the ring. This is preferably accomplished by mounting the ring 16 in position on the face plate 15 and providing one or more reciprocable lapping elements to reciprocate in a substantially radial path across the side face of the ring 16 as it rotates to provide an ultra-refined surface on the side face of the ring 16. In the preferred construction, a pair of lapping heads 67 and 68 are provided having reciprocable lapping sticks 69 and 70, respectively, the ends of which are arranged to engage the side face of the piston ring 16 to be lapped at diametrically opposite positions. A single lapping head may be utilized, if desired, or a plurality of heads may be provided, such as the two heads shown in the drawings, whereby an increased lapping action may be produced to increase the productive output of the machine. The lapping sticks 69 and 70 may be of any cross-sectional shape but for the sake of illustration have been shown as being of a square cross-sectional area made of bonded abrasive material and arranged so that the end face of the stick engages for a lapping operation the side face of a piston ring 16.

The lapping stick 70 is adjustably supported in a slide block 71 which is arranged to slide between a pair of opposed guide plates 72 and 73 (Figs. 4 and 7). The lapping stick 70 is held in adjusted position in the slide block 71 by means of a pair of set screws 74 and 75 which are screw threaded into an end plate which is fixed to the slide block 71. The screws 74 and 75 bear against a shim 76 (Fig. 7) which in turn clamps the lapping stick 70 in adjusted position in the slide block 71.

A hydraulic motor 77 is provided to impart a reciprocatory movement to the lapping stick 70. The motor 77 will not be described in detail, since it is identical with that shown in the prior U. S. patent to Wallace H. Wood, No. 2,212,871 dated August 27, 1940, to which reference may be had for details of disclosure not contained herein. The hydraulic motor 77 comprises a cylinder 78 (Fig. 7) which contains a slidable piston 79.

The piston 79 is connected to one end of a piston rod 80, the other end of which is connected to the slide block 71. The motor 77 is provided with a control valve comprising a hollow pilot valve 81 which contains a slidably mounted shuttle type reversing valve 82. The pilot valve 81 is provided with a valve stem 83 having a pair of adjustable dogs 84 and 85 mounted thereon. The dogs 84 and 85 are arranged in the path of a lug 86 which projects from the slide block 71 and serves automatically to shift the pilot valve 81 to reverse the motor 77. It will be readily apparent from the foregoing disclosure that when the piston 79 is moved back and forth within the cylinder 78, a reciprocatory movement will be imparted to the slide block 71 and the abrasive lapping stick 70.

Fluid under pressure from the control valve 44 passes through a pipe 88 into a chamber 89 (Fig. 8) in the casing surrounding the pilot valve 81 and through ports into a valve chamber. Fluid is exhausted from the motor 77 through a passage 90 and a pipe 91 into the reservoir 40. A throttle valve 92 is provided in the pipe line 91, by means of which the rate of exhaust of fluid from the motor 77 may be regulated as desired so as to control the speed of movement of the piston 79 and also the speed of reciprocation of the lapping stick 70. In the position of the valve 44, fluid under pressure in the pipe 43 passes through a pipe or passage 93 into a valve chamber located between the valve pistons 51 and 52 and passes out through a pipe 94 which connects with the pipe 88 to convey fluid under pressure to the hydraulic motor 77 (Fig. 1).

Similarly, the lapping head 67 is provided with a hydraulic motor 97 for reciprocating the lapping stick 69 in operative lapping contact with the work piece 16. The motor 97 is identical with the hydraulic motor 77, consequently it has not been illustrated in detail. For details of disclosure not contained herein, reference may be had to the hydraulic motor 77 and to the prior U. S. patent to Wallace H. Wood, No. 2,212,871 dated August 27, 1940. The motor 97 is provided with a pilot valve which is actuated by a valve stem 98 (Fig. 1). The valve stem 98 is provided with a pair of adjustable dogs or collars 99 and 100 which are arranged in the path of a lug 101 which projects from the slide block supporting the lapping stick 69. Fluid under pressure passing through the pipe 94 passes through a pipe 102 to provide pressure for actuating the motor 97 to impart a reciprocatory movement to the lapping stick 69. Fluid is exhausted from the motor 97 through a pipe 103 which exhausts into the reservoir 40. A throttle valve 104 is provided in the pipe line 103 by means of which the speed of the hydraulic motor 97 and the speed of reciprocation of the lapping stick 69 may be readily varied and controlled.

In the position of the parts as shown in Fig. 1, fluid under pressure from the pipe 43 passes to each of the hydraulic motors 77 and 97 continuously to reciprocate the lapping sticks 70 and 69, respectively, rapidly across the end face of the piston ring 16 to lap the same during rotation thereof. After a lapping operation has been completed and the valve control lever 57 is shifted into position 57a, the valve piston 52 closes the port at the end of the fluid pressure pipe 93, thus cutting off fluid under pressure from the pipe 94 simultaneously to stop the hydraulic motors 77 and 97.

The hydraulic motors 77 and 97, together with the lapping sticks 70 and 69, respectively, sup-

ported thereby, are arranged so that they may be moved to and from an operative position and so that the lapping sticks 70 and 69 may be maintained yieldably in engagement with the surface being lapped. As illustrated in the drawings, the motor 77 is mounted on the end of a piston rod 105. The other end of the piston rod 105 is provided with a piston 106 which is slidably mounted within a cylinder 107. The piston rod 105 is provided with a central aperture 108. A spring 109 is contained within the aperture 108 and is interposed between the end of the aperture 108 and a slidably mounted plug 110. An adjusting screw 111 is screw threaded through an end cap 112 and serves to facilitate adjustment of the compression of the spring 109 whereby the pressure of the lapping stick 70 on the piston ring 16 may be varied as desired.

The piston rod 105 is held against any rotary movement by means of a guide bar 113 which is fixedly mounted on the outer surface of the cylinder 107. The guide rod or bar 113 passes through a correspondingly shaped aperture 114 formed in or fixedly mounted on the casing of the motor 77. The guide bar 113 is provided with a depending lug 115 which supports a stop screw 116. The stop screw 116 is engaged by a portion of the motor casing 77 and serves to limit the forward advancing movement of the motor 77 and the lapping stick 70 so as to accurately limit the advancing movement of the lapping stick 70. After a lapping operation has been completed, fluid under pressure may be admitted through a pipe 117 into a cylinder chamber 118 to cause the piston 106 together with the motor 77 and lapping stick 70 to move toward the right (Fig. 1) against the compression of the spring 109 to move the lapping stick 70 out of operative engagement with the work piece 16 being lapped.

Similarly, the fluid motor 97 is mounted on the left-hand end of a piston rod 120. The piston rod 120 is provided with a piston 121 at its other end which is slidably mounted within a cylinder 122. The piston rod 120 is provided with a central aperture 123 which contains a compression spring 124. The compression spring 124 is interposed between the left-hand end of the aperture 123 and an adjustable slidably mounted plug 125. An adjusting screw 126 is screw threaded through an end cap 127 which is fixedly mounted on the right-hand end of the cylinder 122 (Fig. 1). The inner end of the screw 126 abuts against the plug 125. By adjusting the screw 126, the compression of the spring 124 may be adjusted as desired so as to provide the desired pressure of the lapping stick 69 on the face of the piston ring 16 being lapped.

In order to prevent rotary motion of the piston rod 120 together with the motor 97, a guide bar 128 is fixedly mounted to the outside of the cylinder 122. The guide bar 128 extends within a correspondingly shaped aperture 129 formed in or fixedly mounted on the casing of the fluid motor 97 so that the motor 97 may slide with the piston rod 120 without any rotary motion. The guide bar 128 is provided with an upwardly extending lug 130 which carries a stop screw 131. The stop screw 131 is arranged in the path of a portion of the motor casing and serves to limit the movement of the motor 97 and the lapping stick 69 in a direction toward the left (Fig. 1). After a lapping operation has been completed and it is desired to move the lapping stick 69 out of operative

engagement with the piston ring 16 being lapped, fluid under pressure is admitted through a pipe 132 into a cylinder chamber 133 to move the piston 121 together with the piston rod 120, the hydraulic motor 97 and the lapping stick 69 in a direction toward the right (Fig. 1).

The pipe 132 is connected to the pipe 117 which in turn is connected to a throttle valve 134 (Fig. 1). The throttle valve 134 is in turn connected by a pipe 135 with the main control valve 44. In the position of the valve 44 (Fig. 1), the pipe 135 connects with a valve chamber located between the valve pistons 52 and 53 which in the position shown is connected to an exhaust pipe 136 leading to the reservoir 40. After a grinding operation has been completed and the valve stem 50 is moved toward the left, the movement of the valve piston 53 toward the left closes the port leading to the exhaust pipe 136 and opens a port so that fluid under pressure within the pipe 43 may pass through a pipe 137 into the valve chamber located between the valve pistons 52 and 53 and passes outwardly through the pipe 135 and the valve 134 simultaneously to move the lapping sticks 69 and 70 out of operative engagement with the piston ring 16 being lapped. The throttle valve 134 located between the pipes 135 and 117 serves to regulate the passage of pressure to and from the cylinder chambers 118 and 133, respectively, so that the rate of movement of the lapping sticks 70 and 69, respectively, into engagement with the work may be readily controlled as desired.

It is desirable that the path of reciprocation of the lapping sticks 69 and 70 be angularly adjustable in order that either a flat or a tapered end face may be lapped on the piston ring 16 as desired. To accomplish this desired result, the lapping heads 67 and 68 are adjustably supported on the transversely movable slide 30. The transversely movable slide 30 is provided with a vertically extending column 140 which serves as a support for the lapping heads 67 and 68. The column 140 is provided with a plurality of vertically arranged T-slots 151, 152, 160 and 161 (Figs. 1, 2 and 5). A rectangularly shaped plate 141 (Figs. 1 and 2) is adjustably mounted on the column 140 by means of mounting screws 142, 143, 144 and 145 and serves as a support for the lapping head 68. The cylinder 107 of the lapping head 68 is formed integral with a sector-shaped plate 146 which is pivotally supported by a stud 147 on the plate 141. The sector plate 146 may be angularly adjusted in a vertical plane relative to the vertically adjustable plate 141. A clamping screw 148 and the clamping screw 145 serve to clamp the plate 146 in adjusted position on the plate 141. The clamping bolt 145 has its head slidably positioned in a T-slot 151 formed in the column 140 and passes through a hole formed in the supporting plate 141 and passes through an elongated slot 150 formed in the sector plate 146. The clamping screw 148 passes through an elongated slot 149 in the sector plate 146 and is screw threaded into the vertically adjustable supporting plate 141 (Fig. 6). It will be readily apparent from the foregoing disclosure that the clamping bolt 145 serves jointly as a binding screw for both the sector plate 146 and the vertically adjustable supporting plate 141.

Similarly, a vertically adjustable supporting plate 155 is adjustably clamped on the column 140 by clamping screws 156, 157, 158 and 159. The clamping bolts 156, 157 have their heads

supported in a vertically arranged T-slot 160 formed in the column 140, and the clamping bolts 158 and 159 have their heads supported in a T-slot 161, also formed and arranged vertically on the column 140. A sector-shaped plate 162 is formed integral with the cylinder 122 of the lapping head 67. The sector plate 162 is pivotally supported on a stud 163. A binder or clamping screw 164 passes through an elongated slot 165 formed in the sector-shaped plate 162 and is screw threaded into the vertically adjustable plate 155. This serves as a means for clamping the sector plate in adjusted angular position so that the path of reciprocation of the lapping stick 69 may be either normal to the axis of rotation of the piston ring 16 being lapped in case a flat side face is desired or at an angle thereto as shown in the drawings for producing a tapered side face on the ring 16. The clamping screw 158 also serves as an additional clamping medium for clamping the sector-shaped plate 162 in adjusted position. The clamping screw 158 passes through an elongated slot 166 formed in the sector-shaped plate 162 and passes through a hole formed in a vertical supporting plate 155. Its head is supported in the T-slot 161 so that when it is clamped in position it serves jointly to lock the sector plate in adjusted position on the supporting plate 155 and also to lock the supporting plate 155 in position on the column 140.

If desired, the lapping sticks 69 and 70 may be moved into operative engagement with the ring 16 to be lapped and maintained in lapping engagement therewith by means of fluid under pressure. A modification of the lapping head 68 has been illustrated in Fig. 9, in which fluid under pressure may be utilized for moving the piston 106 toward the left (Fig. 9) to move the lapping stick 70 into an operative position. Fluid under pressure from the pump 41 (Fig. 1) in this case is conveyed through a pipe 170 (Fig. 9), through a throttle valve 171, a pipe 172, and a manually operable control valve 173, and through a pipe 174 into a cylinder chamber 175 at the right-hand end of the piston 106. Fluid under pressure within the pipe 174 may also pass through a pipe 176 to the other lapping head simultaneously to move both of the lapping sticks into an operative position. By regulation of the throttle valve 171, the speed of movement of the piston 106 may be varied as desired. After a lapping operation has been completed, the valve 173 may be shifted into the dotted line position (Fig. 9) so that fluid within the cylinder chamber 175 may exhaust through the pipe 174 and through a pipe 177 which returns the exhausting fluid to the reservoir 40.

A spring-pressed detent 180 is provided having an arrow point operative end which is arranged to mate with a V-groove 181 formed in the stem 50 of the control valve 44 so that the lapping sticks 69 and 70 (Fig. 1) may be readily moved to an inoperative position in case it is desired to inspect the work piece being lapped. The control lever 57 is moved into position 57b which shifts the valve stem 50 so that the groove 181 is aligned with and engaged by the spring-pressed detent 180, so that the valve piston 53 moves a sufficient distance to cover the port to cut off the pipe 135 from connection with the exhaust pipe 136. The movement also shifts the valve piston 52 toward the left a sufficient distance so that fluid under pressure from the pump 41 passing through the pipe 43 passes through the pipe 137 and through the valve chamber located between

the valve pistons 52 and 53 and out through the pipe 135 simultaneously to provide fluid under pressure within the cylinder chambers 118 and 123, respectively, to move the pistons 106 and 121, respectively, toward the right (Fig. 1), which movement serves to remove the lapping sticks 70 and 69, respectively, from operative engagement with the piston ring 16.

The detent 180 and groove 181 serve as a locating device so that the operator may readily shift the valve 44 into the intermediate position above mentioned or may shift the control lever 57 into the reverse position 57a by merely overcoming the resistance of the detent 180 after a lapping operation has been completed to facilitate removal of the finish lapped piece of work and the insertion of a fresh piece of work to be lapped.

It is desirable to provide an interconnection between the hydraulic control system for controlling and actuating the lapping sticks and the electrical mechanism for controlling the rotation of the work piece. As illustrated in Fig. 1, the actuating plunger of the normally closed limit switch 25 is arranged in the path of movement of the valve stem 50 of the main control valve 44. As shown in Fig. 1, the parts are illustrated in an operative position with the work piece 16 rotating and the lapping sticks in reciprocable engagement with the rotating work piece. After the lapping operation has been completed, the control lever 57 is shifted into position 57a to withdraw the lapping sticks 69 and 70 from operative contact with the work piece 16, stop the reciprocation of the lapping sticks 70 and 69, and move the transverse slide 30 to an inoperative position so that the lapping heads 68 and 67 are moved to an inoperative position.

During the shifting movement of the control lever 57 into position 57a, the end of the valve stem 50 engages and moves the actuating plunger of the normally closed limit switch 25 so as to open the switch, thus breaking a circuit automatically to stop the electric motor 17 and thereby stop the rotation of the face plate 15 and the piston ring 16. Similarly, when a new piece of work has been inserted and it is desired to start a lapping operation, the control lever 57 is shifted from the broken line position 57a (Fig. 1) into the full line position 57, which movement shifts the valve stem 50 toward the right, thus withdrawing it out of contact with the actuating plunger of the normally closed limit switch 25 which allows the switch to close, thus closing a circuit to start the work driving motor 17 to set the face plate 15 and piston ring 16 to be lapped in rotation automatically before the lapping sticks 69 and 70 are in operative engagement therewith.

The operation of this improved lapping machine will be readily apparent from the foregoing disclosure. Assuming all of the adjustments to have been previously made, that is, the sector-shaped supporting plate 146 and 162 angularly adjusted to position the reciprocatory stroke of the lapping sticks 70 and 69, respectively, a work piece, such as a piston ring 16, is inserted in position on the face plate 15, after which the control lever 57 is shifted from broken line position 57a into full line position 57 (Fig. 1). This movement of the control lever shifts the valve stem 50 into the position shown in Fig. 1, which movement allows the normally closed limit switch 25 to close, thus closing a circuit automatically to start the work driving motor 17 which in turn transmits a rotary motion

through the spindle 12 and face plate 15 to the piston ring 16.

The shifting of the valve stem 50 toward the right into the position illustrating in Fig. 1 first serves to shift the valve piston 52 to uncover the port leading to the pipe 94, thus admitting fluid under pressure through the pipe 88 and 102, respectively, which convey fluid under pressure to the hydraulic lapping stick motors 77 and 97, respectively, to start the reciprocatory movement of the lapping sticks 70 and 69, respectively. The valve piston 55 then uncovers the port leading to the pipe 62 to admit fluid under pressure into the cylinder chamber 38 to move the piston 34 together with the transversely movable lap supporting slide 30 toward the left into engagement with the stop abutment 66 to position the slide in an operative position for a lapping operation. Continued movement of the valve into its right-hand end position (Fig. 1) moves the valve piston 53 so as to uncover the port connecting the pipe 135 with the exhaust pipe 136 so as to allow the fluid within the cylinder chambers 118 and 123, respectively, to be exhausted therefrom by means of the released compression of the springs 109 and 124, respectively, which movement serves to shift the lapping heads 77 and 97 so that the lapping sticks 70 and 69, respectively, are moved into operative lapping engagement with the piston ring 16 to be lapped. It will be readily apparent from the foregoing disclosure that the lapping sticks 70 and 69 are reciprocating as they are moved into operative engagement with the work piece 16. As previously described, the pressure of the lapping sticks 69 and 70 in engagement with the work may be controlled by adjustment of the compression of the springs 109 and 124, respectively.

After the lapping operation has proceeded to the desired extent, the control lever 57 may be shifted into position 57a, which movement serves first to admit fluid under pressure to the cylinder chambers 118 and 123, respectively, to move the lapping sticks 70 and 69 out of operative contact with the piston ring 16, after which fluid under pressure is cut off from the pipe 94 to stop the hydraulic motors 77 and 97, respectively, and then finally fluid under pressure is admitted through the pipe 63 into the cylinder chamber 37 to move the piston 34 together with the transversely movable lap supporting slide 30 transversely toward the right (Fig. 1) to an inoperative position to facilitate removal of the piston ring 16 which has been lapped. When the valve stem 50 approaches its left-hand end position, its end engages the actuating plunger of the normally closed limit switch 25 and opens the switch to break the circuit, thereby automatically stopping the work driving motor 17, the face plate 15 and the piston ring 16. The lapped piston ring 16 may then be readily removed and a new work piece, such as a piston ring 16, inserted for the next lapping operation.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a lapping machine having a base, a rotatable work support thereon, means to rotate said work support, a transversely movable slide on said base, a vertically adjustable support on said slide, an adjustable swivel plate on said adjustable support, a lapping head carried by said plate comprising a piston and cylinder, an adjustable spring to move said piston in one direction, a fluid pressure system whereby the piston may be moved in the other direction by fluid under pressure, a piston rod having one end fixedly attached to the piston, a self-contained fluid motor fixedly mounted on the other end of said piston rod, and a lapping element adjustably mounted to be reciprocated by said motor while in operative engagement with a work piece.

2. In a lapping machine having a base, a rotatable work support thereon, means to rotate said work support, a transversely movable slide on said base, a vertically adjustable support on said slide, an adjustable swivel plate on said adjustable support, a lapping head carried by said plate comprising a piston and cylinder, an adjustable spring to move said piston in one direction, a fluid pressure system whereby the piston may be moved in the other direction by fluid under pressure, a piston rod having one end fixedly attached to the piston, a self-contained fluid motor fixedly mounted on the other end of said piston rod, a lapping element adjustably mounted to be reciprocated by said motor while in operative engagement with a work piece, and means to adjust the reciprocatory stroke of said fluid motor and lapping element.

3. In a lapping machine having a base, a rotatable work support thereon, a transversely movable slide on said base which is arranged to move in a direction parallel to the axis of said work support, a pair of lapping heads adjustably mounted on said slide each having a reciprocable lapping element which are arranged to engage a work piece at diametrically opposite points, means independently to adjust each of said heads toward and from the axis of the work support, a fluid motor and a control valve therefor on each of said heads rapidly to reciprocate said lapping elements, and independent means to adjust each of said heads angularly and in a plane normal to the axis of said work support so that adjacent angularly disposed faces on a work piece may be simultaneously lapped.

4. In a lapping machine having a base, a rotatable work support thereon, a transversely movable slide, a pair of lapping heads on said slide each having a reciprocable lapping element arranged to engage the work piece at diametrically opposite positions, independent fluid motors on each of said heads rapidly to reciprocate said elements in a path substantially normal to the axis of the work support, means independently to adjust each of said heads toward and from the work axis, means angularly to adjust the position of said heads on said slide to adjust the path of reciprocation of said lapping elements so that it is either normal to the axis of the work support or at an acute angle to a plane normal to the axis of the work support.
